UNITED STATES PATENT OFFICE

2,328,226

WASHING MACHINE

Irving Nachumsohn, Chicago, Ill.

Application April 12, 1941, Serial No. 383,324

2 Claims. (Cl. 248—152)

My invention relates to washing machines and structures of similar form, and more particularly to the body portions thereof, and one of my objects is to provide a washing machine body or wall formed with reinforcements designed to strengthen the body and fortify the same against strains and stresses incident to the use of the machine.

A further object of the invention is to provide a body of the character mentioned which receives its reinforcements without being drawn or unduly strained, requiring only conventional forming means for its fabrication.

Another object of the invention is to form the body of the washing machine with reinforcing columns which serve in an extended form as legs for the washing machine, thereby incorporating a body, reinforcing means and legs in one piece.

A further object of the invention is to provide a unique method in the formation of the washing machine body, whereby to make its production efficient and economical.

With the above objects in view, and any others which may suggest themselves from the description to follow, a better understanding of the invention may be had by reference to the accompanying drawings, in which—

Figure 1 is a plan view of a metal blank from which the washing machine body is made;

Fig. 2 is a front elevation wherein the reinforcing and leg portions are defined;

Fig. 3 is a top plan view of the showing in Figure 2, a further formation being indicated by dotted lines;

Figs. 4 and 5 are sectional views showing further steps in the formation of the washing machine legs;

Fig. 6 is an edge view, showing an apparatus for rounding and imparting bead formations in the metal of the body;

Fig. 7 is a plan view of the showing in Figure 6;

Fig. 8 is a section on the line 8—8 of Figure 7;

Fig. 9 is a perspective view of the body in a substantially complete form; and

Fig. 10 is an enlarged outside view of a cap supplementing one of the reinforcing elements.

When the body of a conventional washing machine is formed as a sheet metal cylinder, it is customary to apply bars or other reinforcing elements to strengthen the body; also, the legs of the machine must be suitably applied and secured to the body. These additions obviously require separate operations; and their efficiency depends on their strength or the extent to which

they render the body firm to withstand the shocks and strains of use. By forming the improved washing machine body with integral reinforcing and supporting factors, however, greater efficiency in production and durability in use are obtained.

In accordance with the foregoing, specific reference to the drawings indicates the sheet metal blank from which the body is formed at 15. As shown in Figure 1, this blank is of considerable length to provide sufficient material for the body wall and its formations; and the blank is, of course, of a height equivalent to that of the body and legs of the washing machine.

Primarily, the reinforcing formations of the sheet 15 are spaced-off laterally to conform with the positions of the four legs of the machine. Thus, while the main portion of the sheet 15 is employed to form the body wall, the four bottom extensions 16 of the reinforcing formations are designed to form the legs, these extensions being, however, severed from the main portion of the sheet at the sides, as indicated by slit lines 17. The upper portion of the blank is formed with a series of rectangular recesses 18 in line with the legs, these recesses being for a purpose later described.

In order that the body reinforcements and legs may receive their initial form, the sheet 15 is laid in the receptacle of a die 19 which has a substantially semi-octagonal form, the forming member 20 of the die being applied from above to impart a corresponding form to the metal, so as to define the reinforcing unit 16a and the frontal portion of the leg 16. It is understood that the above impressing operation will be imparted in each zone designed to receive a reinforcing formation and leg extension; and the operations will apply consecutively in a lateral direction, so that the blank after treatment will have contracted from the width of Figure 1 to that of Figure 2.

While the above-described impressing operations on the blank 15 will create a sheet having flat sections alternating with projecting semi-octagonal column formations, the material of the legs 16 will extend with wings 21 and 22 in a rearward direction, the wings 22 being designed with a greater depth than the wings 21. It is intended that the legs be made in tubular or box form, and a pair of slides 23 and 24 are therefore employed to fold the wings for the completion of the legs. The slide 23 is moved inwardly a sufficient distance to procure the folding of the wing 21 upon the press 20; and the slide 24 is similarly moved to procure the overlapping of the folded

wing 21 by the wing 22, so that the form of the leg appears as in Figure 5. While any mechanism may be employed to advance the slides 23 and 24 to procure the desired results, I prefer to employ an arched descending ram 25 formed with arms 26 having inclined inner faces 27. The outer faces of the slides 23 and 24 have surfaces 28 of similar inclination to the faces 27, so that these act as cams to advance the slides 23 and 24 when the ram 25 is lowered, as is common in a set of cam dies.

With the body sheet given the vertical reinforcements described, it is also necessary that it be laterally reinforced to retain its circular shape after it is formed into the body wall. This type of reinforcement is in the form of a concave bead 30 near the top, a convex bead 31 some distance from the bottom, and an inward lip or curl 32 at the bottom. Figures 6 to 8 show roller means 33 and 34 shaped to produce the reinforcing elements mentioned while a lateral roller 35 acts to round the sheet into the cylindrical form. However, the rollers 33, 34 and 35 are formed with cut-out portions 33a, 34a and 35a, respectively, to clear the consecutive reinforcements 15a as the rollers advance the sheet 15 in accordance with their rotation, as indicated by the arrows in Figure 6; and the motion of the rollers is synchronized by a suitable gearing (not shown) to insure the positive and accurate forming of the work. Dotted lines in Figures 6 indicate the rolling course of the sheet 15 to assume the cylindrical wall formation; and Figure 9 shows that a short wing portion 15b at one end of the sheet 15 is on the inside and overlapped by the opposite end of the sheet when the same assumes the cylindrical form, at which time the joint so formed is spot-welded in several places to render the closing of the wall permanent.

It is evident from Figures 2 and 9 that the recess 18 leaves an opening in the top of the body 15 above each reinforcement 15a. Rather than impose a special drawing process on the reinforcements to top them off, I choose to apply a separate cap over each reinforcement, such a cap being indicated at 37 in the right-hand portion of Figure 2. Figure 10 shows the frontal side of the cap as the same is applied to surmount the reinforcement; and it is indicated that the cap has the general formation of the same in its lower portion, while receding toward its upper edge to terminate substantially flush with the body 15. In order that the cap may be fitted over the reinforcement, it is seated with its side portions

in notches 18a made in the corners of the recess 18, such side portions then being continued with outward flanges 38 which lie against the back side of the body sheet 15 and may be spot-welded thereto for purposes of retention.

It will be evident from the above description that the novel washing machine body is not only formed in one piece with its legs, but uses columns coextensive with the same to reinforce it at lateral intervals, so that in combination with the bead reinforcements above and below the finished body assumes strength and rigidity, all without the need of separate or applied reinforcements, bolts, rivets or other fastening means. With the above-described method of manufacture considered, the novel washing machine body becomes a product which is economically produced, durable in use and neat in appearance. In fact, the reinforcing elements, capped as described, add ornamental value while retaining simplicity of design. Also, the columnar reinforcing elements contribute an advantage where a closed air space is provided between the washing machine body and its internal tub, for retaining the heat of the tub contents. Where applied metallic reinforcements would tend to dissipate heat from an unextended cylindrical wall, the chambers in the instant wall columns form extensions of the said air space, augmenting the heat-insulating properties thereof. In conclusion, the outstanding feature of the improved washing machine body is the one-piece construction to form the combination of a body, reinforcing elements therefor and supporting legs.

While I have described the improved structure and method along specific lines, it is possible that various minor changes or refinements may be made therein without departing from the principle involved, and I desire to consider all such changes or refinements as coming within the scope and spirit of the appended claims.

I claim:

1. In a washing machine or the like, a wall designed to enclose an insulating space around the tub of the machine, and means to augment said space comprising a series of laterally-spaced reinforcing outward projections from said wall, said projections forming internal pockets communicating with said space.

2. The structure of claim 1, said projections being columns extended downwardly to form legs for said wall.

IRVING NACHUMSOHN
